M. R. BERGER

GUTTER HANGER CIRCLE

Filed June 25, 1927

UNITED STATES PATENT OFFICE.

MATTHEW RUSSELL BERGER, OF PHILADELPHIA, PENNSYLVANIA.

GUTTER HANGER CIRCLE.

Application filed June 25, 1927. Serial No. 201,406.

The leading object of the present invention is to provide a gutter hanger circle the shank of which is so formed that a plurality of spaced, apertured, individual protuberances are provided for snugly fitting within the groove of a channel bar to prevent lateral or sidewise movement of the circle when the latter is in attached position.

A further object is to provide a structure as set forth in the leading object in which the apertured protuberances are of circular form and may be stamped out of the metal forming the circle shank.

A further object is to provide a cheaper, more efficient, more practical, more workman ship like, and neater appearing device of the character stated.

Other and further objects not at this time set forth will hereinafter appear.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in side elevation of a gutter hanger circle embodying the invention and secured to a conventional channel iron.

Fig. 2, is a view in cross section taken upon the line 2—2 of Fig. 1.

Fig. 3, is a fragmentary view in side elevation of the shawls of the gutter hanger circle; and

Fig. 4, is a view in section taken upon the line 4—4 of Fig. 3.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Heretofore it has been the accepted trade practice to provide the shank of a gutter hanger circle with a vertical and apertured web for detachably engaging within the groove of a channel iron. Prac-

tice dictates that this web formation is not as efficient in use nor as cheap to make as is desirable in an article of the class under consideration. In the circle in which the apertured rib is employed it requires two operations in the rib and aperture formation. That is, after the circle per se is formed, the web is subjected to two stamping operations, namely: one to form the rib and the other to form the apertures. According to my present invention no rib is required upon the circle web so that an operation is dispensed with, as is obvious. In the conventional form of gutter hanger circle it is also found that lateral movement of the circle may take place because the vertical, curved rib of the circle does not fit squarely and has the tendency to move about its vertical axis. This is undesirable. By the construction about to be described these disadvantages are obviated.

Referring now to the drawings in detail, the reference numeral 10 designates a gutter hanger circle of the type shown in Letters 80 Patent granted to Matthew Russell Berger, and numbered 1,577,163 from which a clear understanding of the general structure and function of gutter circles of this general character may be had. The vertical web 11 has pressed, stamped, or otherwise formed therein the vertical aligning row of eyes or apertures 13 around each of which is formed at one side thereof, thickened, annular, reinforcing walls 14 which project a short distance from the web 11 on its inner surface, as seen in Figs. 2 and 4, and have their outer terminals or surfaces 15 finished or faced off so that said surfaces 15 are in the same vertical rectilinear plane. By reason of this construction it will be apparent that when the circle 10 is assembled with respect to the channeled bar 16, as seen in Figs. 1, and 2, the surfaces 15 will abut against the wall or surface 17 of said channeled bar and when the screw, bolt, or other fastening device 18 is passed through one of the holes or eyes 13 and an aligning eye or hole 19, as will be understood from Figs. 1 and 2, the web 11 of the gutter circle, together with its protuberances or surfaces 15, are secured rigidly and immovably against the wall 17 of the channeled member 16, so that there will be no space or play between the surfaces 15 and 17 or between the web 11 of the circle and its supporting channeled bar 16. By my novel construction the circle 10 is rigidly and im-

movably secured to the channeled member 16 and there is no liability or opportunity for lateral or other movement of said circle 10 with respect to its support, which is a very desirable feature in devices of this character, since it is essential that the circle be rigidly and immovably secured with respect to its support.

It will be understood that the novel characteristic features of my invention, as seen in Figs. 2, 3, and 4, are adapted to coact with any gutter circle support, such as for instance a T-shaped or angular shaped, which are full equivalents of the channelled construction shown; and while I have shown my invention in the present instance as coacting with a channelled support, it will be apparent that the same is equally adapted to other supports of different cross section as will be apparent to those skilled in the art.

What I claim is:

1. In a device of the character stated, a gutter circle web of integral structure and stamped or formed from a blank, said web having formed therein a series of apertures, one side of said web being provided with annular, reinforcing walls projecting therefrom, each wall completely surrounding an aperture, the inner faces of said walls being faced in vertical alignment so that a series of rectilinear aligning bearing surfaces are formed on the web of said circuit, contiguous to its support.
2. In a device of the character stated, a gutter circle support web of integral structure and stamped or formed from a blank, said web having formed therein a series of apertures, one side of said web being provided with annular, reinforcing walls projecting therefrom, each wall completely surrounding an aperture, the inner faces of said wall being faced in vertical alignment so that a series of rectilinear aligning bearing surfaces are formed on the web of said circle, contiguous to its support, in combination with a channelled supporting member against which the aligning surfaces of said walls are secured, and a fastening device common to said web and said channeled member for penetrating an opening as surrounded by one of said annular walls.

MATTHEW RUSSELL BERGER.
